UNITED STATES PATENT OFFICE.

WALKER W. McCARROLL, OF ARLINGTON, NEW JERSEY.

MACHINE FOR RECTIFYING ELECTROTYPEs.

1,112,544.

Specification of Letters Patent.

Patented Oct. 6, 1914.

Application filed July 25, 1911. Serial No. 640,500.

To all whom it may concern:

Be it known that I, WALKER W. McCARROLL, a citizen of the United States of America, and a resident of Arlington, Hudson county, New Jersey, have invented certain new and useful Improvements in Machines for Rectifying Electrotype, of which the following is a specification.

This invention relates to machines for rectifying electrotype plates and the object of the invention is to improve in several particulars the machine for rectifying electrotype as the same is shown and described by me in a pending application filed April 6, 1911, Serial Number 619,203.

More particularly this invention relates to improvements in the means for operating the glass block and in several novel and useful mechanisms for adjusting the various parts of the machine with a view to increase the efficiency of the machine and its scope of work.

Other objects of the invention are to provide improved supports for the rectifying tools.

The invention will be more fully understood by the following detailed specification read in connection with the accompanying drawings in which—

Figure 1 is a front elevation of the machine. Fig. 2 is a detail view of a locking mechanism. Fig. 3 is a side elevation looking from the left in Fig. 1 and with parts removed and parts in section for the sake of clearness. Fig. 4 is a fragmentary plan view of the upper operating levers. Figs. 5 and 6 are detail views of an adjusting mechanism for regulating the stroke of the glass. Fig. 7 is a rear detail view of parts of the pressure means for the hammer rod. Fig. 8 is a detail view of the tension device shown in Fig. 7. Fig. 9 is a fragmentary view showing a modified form of tool holder. Fig. 10 is a detail view of the parts shown in Fig. 9. Fig. 11 shows another modified form of tool holder, and Fig. 12 is a diagrammatic view of the glass block and line of tools shown in Fig. 11.

In the application above referred to I have described in detail the construction and operation of the entire machine. Those features, therefore, which are common to the two applications will in the following be referred to in such details only as are necessary for the understanding of this invention.

Referring to the drawings the numeral 9 represents a glass block which is suitably supported in a framework 10 adapted to slide vertically on posts 11 secured to a horizontal slide 12 guided in the frame 13. Below the bed plate 14 there is a tool slide 15 suitably guided in the frame and which carries the tools 16, which may be arranged in three rows of five each as shown. The tool slide and the glass slide are connected by the rods 17, 17 joined by the rack piece 18 having a rack 19 operated by the toothed segment 20. The latter is operated by a handle 21 to move the slides horizontally to position any one of the tools in the center of the machine which is indicated by a needle 22. The latter is fast in a sleeve 23 carried by the upright weighted member 24 which passes through a slot 12' in the slide 12 as shown in Fig. 1. From this it will be seen that the tools and the glass may be operated sidewise independently of the member 24, the rod 25 of the glass carriage passing loosely through the sleeve 23.

It will be understood in a general way that the glass is provided on its under surface with marks which correspond with the position of the various tools, and that the latter are operated upwardly to punch up the low places in the electrotype which rests on the bed plate while the glass is operated downwardly to provide a resistance against the blows of the tools.

26 is a hammer rod which may be adjusted under any one of the three rows of tools as will be readily understood from Fig. 3. To this end the hammer rod passes through a bearing block 27 which may be moved forward or backward by the lever 28 connected to another lever 29 operated by a handle 30. The hammer rod is supported in a bifurcated free end of a pressure arm 31 which rests on a lug 32 and the rear end of which is pivoted on a stud 33 fast in a block 34 guided on rods 35, 35. A spring 36 keeps the block 34 upward against a cam 37 fast on a shaft 38 journaled in a small framework 39 suitably attached to the main frame 13.

66 is a small pulley fast on the shaft 38 for the purpose of turning the latter to lower block 34 and stud 33.

40 is a coiled spring around the hammer rod and which engages an adjusting nut 41. The hammer rod is for the purpose of put-

ting a pressure on the tools before the hammer is operated so that slight blows of the hammer will suffice for the operation of the tool and the impression of the latter on the 5 electrolyte may be adjusted or regulated to a nicety, at the same time the noise and wear on the machine is reduced.

The operation of the hammer and the hammer rod is accomplished by the following means. 42 is a constantly rotating shaft 10 to which power is applied in any suitable manner and which carries a cam 43 adapted to engage a cam roll 44 on the arm 31. On the shaft 42 is also secured a hammer release cam 45 having a deep notch 46. 47 is the hammer which is secured to an arm 48 loosely pivoted on a transverse rod 49. Adjacent the arm 48 there is also loosely journaled on the rod 49 a bell crank 50. A rod 20 51 is connected to the upper arm of the bell crank at 52 and passes downwardly through the end 53 of the arm 48, a coiled expansion hammer spring 54 being interposed between the bell crank and the hammer arm 25 as shown. The forward end of the bell crank 50 is pivoted at 64 to the upper end of a link 55 which in turn is pivoted at 56 to the treadle 57 pivoted at 58 and operated by a foot lever 59. The treadle carries an 30 upright arm 60 to which is pivoted a rod 61 which passes through the link 55 beyond which it carries a coiled spring 62. The hammer arm 48 carries a cam roll 63 which engages the release cam 45. A pulley 65 is 35 journaled on the rod 49 but is fast to and moves with the bell crank 50. A cable 67 connects the pulley 65 with the aforesaid pulley 66. It will be seen that when the treadle 57 is depressed the link 55 is raised 40 and the bell crank 50 is tilted rearward thus compressing the spring 54 and a pressure is put on the hammer arm 48 tending to force the hammer upwardly. This, however, is prevented by the cam 45 until such 45 time when the notch 46 permits an upward movement of the cam roll 64 when the hammer 45 is caused to deliver an upward blow on the hammer rod by the pressure of the hammer spring 54. At the same time the bell crank 50 is tilted, the pulley 65 is also 50 operated and through the cable 67 and pulley 66 the shaft 38 is rotated. This turns the cam 37 to lower the block 34 and the stud 33 as described and simultaneously there- 55 with the cam 43 engages the cam roll 44 to lift the pressure arm 31. The cams 43 and 45 are so timed that the pressure is put on the hammer rod immediately prior to the blow of the hammer. Thus the depression 60 of the treadle causes the lowering of the stud 33 and the cam roll 44 to enable the cam 43 to again lift the arm 31 to press the hammer rod against the tools and also compresses the spring 54 which in turn acts on 65 the hammer. The hammer rod is lowered

positively after the blow by a spring 68 and the treadle spring 62 serves to restore the treadle to normal position.

When the pressure on the treadle is removed the stud 33 is raised by the rotating 70 of the shaft 38 in the reverse direction. This may be accomplished by the construction shown in Fig. 8 where it will be seen that the shaft 38 carries another pulley 69. A cable 70 is fast to the latter and passes down 75 over a pulley 71 and upward again, where it is secured to the frame 39. A spring 72 forces the pulley 71 downward. It will be seen that the stud 33 is moved up and down perpendicularly so that the cam 43 will engage the cam roll 44 at the same time during each revolution. In the application above referred to the pivot of the pressure arm is operated by an eccentric which causes a slightly forward and backward motion of 80 the cam roll 44 thus introducing a disturbing factor in the operation.

On the shaft 42 is a cam 73 on which run two cam rolls 74 carried by a fork 75 to which is secured a rod 76. The top of this 90 rod carries a head 77 to which is secured two other rods 78 and 79 suitably guided in the frame as shown. The rod 79 passes through the end of the lever 80 which operates the above mentioned member 24 for reciprocating the glass. The lever 80 is pivoted at 81 to a link 82 which is pivoted at 83 to the frame to take up play. On each side of the lever 80 there is on the rod 79 a spring 84 adjustable by nuts 85.

On the frame there is pivoted a member 86 for adjusting the position and the stroke of the glass. See Fig. 5. This member 86 is in the form of an upper and lower bell crank 87, 87 having a hub 88 pivoted on a 100 vertical adjusting screw 89 which is journaled in the frame at 90, 90. The bell cranks carry set screws 91 and 92. This adjusting member may be thrown from one side to another around the screw 89 to bring the set screws into line with the lever 80, see also Fig. 4. A spring latch 93 keeps the member in either the one or the other position as will be clearly seen in Fig. 6. The screw 89 is for the purpose of adjusting the position 105 of the adjusting member.

It will be seen from Fig. 1 that the left end of the lever 80 may be raised or lowered by adjusting the member 86 which positions the glass above the bed plate for a 110 thick or a thin electrolyte and by adjusting the screws 91 or 92 different strokes of the lever 80 are obtained.

The double springs 84 are for the purpose 115 of making the operation of the glass smooth and to eliminate noise by alternately serving as cushions for the stroke of the lever 80. The operation is more smooth and free from sudden jars because as the lower spring lifts the lever 80 as far as the set screws 91 or 92 120

will permit, further movement of the rod 79 results in compression of said spring while the upper spring cushions the upward movement of the lever and on the return stroke 5 the upper spring forces down the lever 80 against the lower spring. I have found in practice that by the coöperation of the member 86 and the double springs 84 I am able to regulate the operation of the glass so as 10 to barely lift the same from the electrotype and much better work may be done on the machine. The lever 80 is normally locked by a stop 94 on a stud 95. A set screw 96 in the lever 80 rests on the stop but when the 15 latter is moved down the lever 80 is free to reciprocate. The stop is operated from the treadle 57 by a cable 97.

It will be understood from the foregoing and the application referred to that during 20 the normal operation of the machine the electrotype rests on the bed plate and that when the treadle is depressed the lever 80 is released and the glass is free to operate while for each revolution of the shaft 42 a 25 tool is operated by the hammer upwardly against the glass, and that the latter and the tools may be adjusted sidewise of the machine from time to time as the work progresses. During this operation the stroke of 30 the lever 80 is regulated by the set screws 91, the member 86 having first been properly adjusted. Before and after the rectifying proper the electrotype plates require straightening or leveling and this is accomplished 35 by a hammer which is caused to operate on the member 24 in a manner similar to the operation of the hammer 47 on the hammer rod. The result sought to be accomplished is that of delivering hammer blows on the 40 member 24 while the latter is pressing the glass down on the electrotype as thereby excessive pounding on and perhaps cracking of the electrotype is avoided. For this purpose I provide a hammer 97 carried by an 45 arm 98 pivoted on the frame at 99 and oscillated through the instrumentality of a short arm 100 and a link 101 pivoted on a block 102 which latter is operated by the aforesaid rod 78 by double springs 103. Hence the 50 block 102 is operated in a manner similar to the operation of the lever 80 as above described. The springs 103 are adjustable by nuts 104. Normally the block 102 is locked by a cam 105 operated by a handle 106, see 55 Fig. 2.

A rod 107 abuts the block 102 from below and is kept upward by means of a spring 108. The rod 107 is connected to a treadle 60 109 by a link 110 so that when the treadle is depressed the rod is moved down, and at the same time the lever 80 is released because the cable 97 is connected by a cable 111 to the said treadle 109 as shown in Fig. 1.

When it is desired to straighten an electrotype the member 86 is swung around to

bring the screws 92 over the lever 80 as above explained. Thereafter the cam 105 is rotated by the handle 106 to free the block 102. The handle 106 may then rest on a stop 112. When now the treadle 109 is depressed the stop 94 is moved down to release the lever 80 and the rod 107 is also moved down to free the block 102 which then is reciprocated by the rod 78 to operate the hammer 97. 70

The springs 84 and 103 are so adjusted that during the combined operation of the glass and the hammer 97, the latter descends a little later than the glass, which at this time has a greater stroke due to the adjustment of the block 86 and the screws 92. The result is that the glass descends to press the electrotype down and immediately thereafter the hammer 97 delivers the blow. The advantage of having the member 86 is now apparent because all the operator has to do after the setting of the set screws 91 and 92 is to swing the member one way or another to obtain the desired stroke of the lever 80 and the glass. Thus repeated adjustments for each different operation for either straightening the plate or rectifying the same are eliminated. 85 90

113 is a treadle shoe operated by levers 114 to regulate the depth to which the treadle 57 may be depressed. 95

Referring now to Figs. 9 and 10 it will be seen that the tools 16 are carried in a segment shaped tool holder 144 suitably pivoted at 115 and operated by a toothed segment 116 and a rack 117 which latter is connected by a brace 118 to the rod 17 fast in the glass slide 12. The brace 118 may be operated by the means above described for operating the toolholder and glass or other suitable mechanism may be employed. It will be seen that as the glass is moved laterally, the tool holder 144 is oscillated to bring the proper tool into the central position. 100 105

In Fig. 11 I have shown a rotating glass carrier 119 while the tools are set in the tool holder 120 in a single row. 110

Fig. 12 illustrates diagrammatically the relative position of the tools and the marks on the glass. The line of the tools is marked 121 and 122 are the tool marks on the glass. The glass is rotated from the shaft 123 by the bevels gears 124, 124. The shaft 123 carries another gear 125 which drives the gear 126 on the shaft 127. This latter carries a gear 128 which engages a rack 129 provided with teeth 130 for the operation of the toothed segment 131 as will be clear from the drawing. By turning the handle 132 the glass is rotated and the tool holder 120 oscillated together. 120 125

It will be seen that I have provided several new elements in machines of this character to enable the operator to operate the machine with as little delay as possible, at 130

the same time providing for quick action of the various parts of the machine and the adjusting devices which are necessary when the machine is to turn out a high grade 5 product.

I claim:—

1. The combination of means for supporting an electrotype, a movable member having a glass block adapted to be operated to 10 straighten the electrotype, a hammer and mechanism for operating the latter and the said member to cause the latter to press against the electrotype and to cause the hammer to strike a blow on the said member after the said glass block has been 15 pressed against the electrotype.
2. The combination of means for supporting an electrotype, a glass block suspended above the same, means for operating 20 the said glass block to exert a pressure on the electrotype, a hammer and means for operating the hammer to deliver a blow on the said glass block after the latter has been pressed against the electrotype.
3. The combination of means for supporting an electrotype, means adapted to be operated to straighten the electrotype and comprising a glass block for exerting a 25 pressure on the electrotype and a hammer 30 for delivering a blow on the said glass block and mechanism for operating the aforesaid means whereby the glass block is caused to move toward the electrotype in advance of the operation of the said hammer.
4. The combination of means for supporting an electrotype, a glass block suspended above the said supporting means, mechanism for reciprocating the said glass block, a pivoted adjusting block and means for setting 35 the same into two different positions to regulate the operations of the said glass block.
5. The combination of a glass block, supporting means therefor, a hammer adapted 45 to strike the said supporting means, mechanism for operating the said glass block and the said hammer, vertically reciprocating rods, springs carried by the said rods and adapted to engage on the top and on the 50 bottom of the said operating means for the hammer and the glass block and means for adjusting the tension of the said springs.
6. The combination of a glass block and a hammer adapted to be operated to 55 straighten an electrotype, vertically operated rods for actuating the said glass block and hammer at the same time, springs carried by the said rods, means for operating the latter and means for adjusting the said 60 springs to cause the said glass block to descend in advance of the said hammer.
7. The combination of a glass block, a lever for operating the same, a pivoted link supporting the said lever, springs engaging 65 the latter on the top and the bottom thereof,

a pivoted adjusting block, stops carried by the latter and adapted to coöperate with the said lever to limit the motions thereof, means for adjusting the tension of the said springs and means for actuating the latter 70 to operate the said lever.

8. The combination of a plurality of rectifying tools, a hammer rod, an arm engaging the same, a cam for operating said arm but normally out of engagement therewith, 75 a guide block, means for pivoting the said arm on the same, means engaging said guide block to keep the said arm out of engagement with the said cam and mechanism for lowering the said guide block perpendicularly 80 to bring the said arm into engagement with the said cam.

9. The combination of a plurality of rectifying tools, a hammer rod, an arm engaging the latter, a cam for operating said arm 85 but normally out of engagement therewith, a guide block supporting the one end of said arm, a cam for operating the said guide block vertically to lower the said arm into operative proximity to the said first named 90 cam and means for operating the said guide block cam.

10. The combination with a plurality of rectifying tools, a hammer rod, a hammer for striking the latter to operate the said 95 tools, mechanism for keeping the hammer in a given inactive position and for periodically releasing the same, means for lifting the said hammer rod to press against the said tools and means for operating the said 100 hammer to strike the said hammer rod when the hammer is released.

11. The combination of a plurality of rectifying tools, a hammer rod, a hammer for striking the latter to operate the said 105 tools, a cam for keeping the said hammer in a given inactive position and for periodically releasing the same, a second cam for lifting the said hammer rod to press against the said tools and a spring for operating 110 the hammer to strike against the said hammer rod when the hammer is released.

12. The combination of a plurality of rectifying tools, a hammer rod, a hammer for striking the latter to operate the said 115 tools, a cam for keeping the said hammer in a given inactive position and for periodically releasing the same, a second cam for lifting the said hammer rod to press against the said tools, a hammer spring for actuating 120 the hammer to strike against the said rod when the hammer is released and means for rotating the said two cams.

13. The combination of a plurality of rectifying tools, a hammer rod, a hammer for 125 striking the latter to operate the said tools, a cam in engagement with the said hammer to keep the same inactive and provided with a cut out portion for periodically releasing the hammer, a pressure arm in en- 130

gagement with the said hammer rod, a treadle, means operated by the latter for lowering the said arm, means for lifting said pressure arm into engagement with the said tools before the said hammer is released and a spring for actuating the hammer to strike against the said hammer rod after the hammer is released.

14. The combination of a plurality of rectifying tools, a hammer rod, a hammer for striking the latter to operate the said tools, a cam in engagement with the hammer to keep the same inactive and provided with a cut out portion for releasing the hammer, a pressure arm in engagement with the said hammer rod, a treadle, means operated by the latter for lowering the said pressure arm, means for lifting the latter into engagement with the said tools before the hammer is released, a spring for actuating the hammer to strike against the said hammer rod and means for automatically lifting the said pressure arm after the hammer has been actuated.

15. The combination of a glass block bearing tool marks on its lower surface, a plurality of tools supported below the said glass block and means for reciprocating the latter and the tools simultaneously in a rectilinear horizontal direction.

16. The combination of a glass block bearing tool marks on its lower surface, a plurality of tools supported below the said glass block, means for reciprocating the latter and the tools simultaneously in a rectilinear horizontal direction and means for operating the glass block and the tools in a vertical direction.

17. The combination of a plurality of rectifying tools, a glass block supported above the same and adapted to coöperate therewith, means for operating the said glass block and tools together in a horizontal direction and means for operating the glass block independent of the said tools.

18. The combination of a glass block, a plurality of rectifying tools below the same, means for moving both the said glass block and the said tools manually in a rectilinear horizontal direction to place one of the said tools in a given position and automatic means for operating the said glass and the one said tool toward one another.

19. The combination of a frame, guides formed in the same, a glass slide movable in said guides, a glass carriage mounted on the said slide and movable therewith and means for operating the said glass carriage at an angle to the said glass slide.

20. The combination of a frame, a glass slide, means for operating the said glass slide on the said frame, posts in said glass slide, a glass carriage mounted to move on the said posts, means for operating said glass slide horizontally and means for op-

erating the said glass carriage on the said posts.

21. The combination of a plurality of rectifying tools, a hammer rod, a hammer for striking the latter to force one of the said tools upward and means for causing the said hammer rod to exert a pressure on the said tool before the hammer strikes the hammer rod.

22. The combination of a plurality of rectifying tools, a hammer rod, a hammer for striking the said hammer rod to force one of the said tools upward, means for causing the said hammer rod to exert a pressure on the said tool before the hammer strikes the hammer rod and means for adjusting the pressure.

23. The combination of a plurality of rectifying tools, a hammer rod, a hammer for striking the latter to force one of the said tools upward, mechanism for causing the said hammer rod to exert a pressure on the said tool, means for adjusting the blow of the hammer and mechanism for causing the said pressure to increase as the blows of the hammer become stronger.

24. The combination of a plurality of rectifying tools, a hammer rod, a hammer for striking the latter to operate one of the said tools, and mechanism for pressing the said hammer rod against the tool to be operated and for actuating the said hammer.

25. The combination of a plurality of rectifying tools, a hammer rod, a hammer for striking the latter to operate one of the said tools, means for setting the said hammer rod to operate on a given tool and means for operating the hammer to strike a blow on the said hammer rod.

26. The combination of a glass block, a plurality of rectifying tools, means for moving the said block and the tools simultaneously in a horizontal direction, a hammer rod, means for pressing the same against any one of the said tools and a hammer for striking the said hammer rod to operate the said tool against the said glass block.

27. The combination of a plurality of rectifying tools, a hammer rod, an arm engaging the latter, a cam for periodically lifting said arm to press the said hammer rod against one of the said tools, a hammer and means for operating the said hammer and the said cam.

28. The combination of a plurality of rectifying tools, a hammer rod, an arm engaging the same, a cam for operating said arm but normally out of engagement therewith, a hammer and mechanism for operating the said hammer and for bringing the said arm into engagement with the said cam to cause the latter to lift the said arm to cause the said hammer rod to press against one of the said tools before the hammer is operated.

29. The combination of a plurality of rectifying tools, a glass block supported above the same, means for operating the said block and the said tools together, a hammer rod, means for positioning the latter under a given tool, a hammer mechanism for causing said hammer rod to press against one of said tools and means for operating the said hammer to strike a blow against the ham-

mer rod after the latter has been pressed against the said tool.

Signed at New York, N. Y. this 20 day of July 1911.

WALKER W. McCARROLL.
